BREAD SLICER

Robert J. Beutel, Brooklyn, N. Y., assignor to
 American Machine & Foundry Company, a
 corporation of New Jersey

Application November 9, 1934, Serial No. 752,344
 Renewed May 28, 1938

18 Claims. (Cl. 146—153)

The invention relates an improved bread slicer, and more particularly to novel means for feeding the loaves of bread through the slicing machine, its main object being to propel the loaves at a relatively high speed to the slicing unit thereof and then retard the speed while the loaf is being sliced in order to obtain a greater proportion of useful slicing time out of the cycle of operation.

This object in the present invention is accomplished by means of a double pawl and ratchet mechanism, the pawls being controlled from a double cam. One pawl through the action of its cam drives the ratchet and conveyor rapidly, while the second pawl is actuated from the other cam to drive the ratchet and conveyor at a slower speed. By advancing the loaves through the slicer at a slow speed a clean cut and even thickness of slice is assured.

With this and other objects not specifically mentioned in view, the invention consists in certain constructions and combinations hereinafter fully described and then specifically set forth in the appended claims.

In the accompanying drawings which form a part of this specification and in which like characters of reference indicate the same or like parts:

Fig. 1 is a side view of the improved bread slicer equipped with the novel loaf feed;

Fig. 2 is an enlarged detail view of the pawl and ratchet driving mechanism; and

Fig. 3 is a side view of the same.

In carrying the invention into effect there is provided a chute adapted to receive a single file of loaves of bread, a slicer unit, and means for separating loaves from said file and advancing them to the slicer unit at a relatively high speed and advancing them through the slicer unit at a relatively low speed. In the best constructions contemplated said means includes conveyor chains, driven and idler sprockets over which the chains are trained, cam-actuated fingers adapted to arrest the leading loaf in the file and release it to permit it to slide down the chute into the path of the flights, and mechanism for driving the driven sprockets at a relatively high speed and then at a relatively low speed. In the best constructions the mechanism for driving the driven sprockets at alternately high and low speed includes a shaft to which the sprockets are fast, a ratchet fast to the shaft, arms loosely mounted on the shaft, spring-pawls mounted on the arms to engage the teeth of the ratchet, means for vibrating the arms to cause said pawls successively to engage the teeth of the ratchet

and drive the shaft at alternately different speed, and adjusting means for varying the amplitude of the vibratory motion of the arms.

These various means and parts may be widely varied in construction within the scope of the claims, for the particular machine selected to illustrate the invention is but one of many possible concrete embodiments of the same. The invention, therefore, is not to be restricted to the specific construction shown and described.

Referring to the drawings, the loaves L are placed on infeed chute 10 which is supported by the side frames 11 and brackets 12 attached to the frames 11. The chute 10 has adjustable side guides 13 which are attached to rods 14 slidably in the brackets 15 and held in position by set screws 16.

The leading loaf L of the file of loaves in chute 10 stops against the fingers 17 fast on cross shaft 18 supported in bearings of the brackets 12. The fingers 17 are actuated from a cam plate 19 mounted on shaft 20, said cam being engaged by a cam roller 21 carried by a cam lever 22 fulcrumed on a stud 23 set in bracket 24, the other end of lever 22 being connected to one of the fingers 17 by rod 25. Each revolution of cam 19 brings its raised portion 26 into engagement with roller 21, thereby raising the same and causing the rod 25 and fingers 17 to descend and thus free the loaf. The fingers 17 remain down until the raised portion 26 of cam 19 has passed the roller 21, whereupon a torsion spring 27 on shaft 18 raises the fingers 17 into position to arrest the following loaf.

The loaf thus freed slides along chute 10 into the path of one of the flights 28 carried by the double conveyor chains 29 and traveling in longitudinal slots on the bottom of the chute 10. The chains 29 run over driven sprockets 30 and over idler sprockets 31, the former being attached at the ends of shaft 32 and the latter loosely mounted on shaft 33 and said shafts being supported by side frames 11. The conveyor 29 is driven at a predetermined speed by means of the double cam 34 having in one of its faces a cam groove receiving a cam roller 35 of an arm 36 integral with the slotted arm 37. A link 38 is connected to the arm 37 by a pin set in a block fastened in the slot of arm 37, and pivotally connected to arm 39 of the gear segment 40, the block being adjustable in the slot of the arm 37 to regulate the amplitude of the oscillating motion imparted to gear segment 40. The segment 40 meshes with a gear sector 41 loosely mounted on shaft 32 (Fig. 2) and provided with

an integral arm 42 which carries a stud 43 on which is pivoted a pawl 44 engaging with a tooth 45 of ratchet 46 keyed on shaft 32. During the forward motion of the pawl 44 the loaf is advanced rapidly a distance corresponding to the space between the loaves on conveyor 29 until the loaf engages the knives of the slicer, the amplitude of the oscillation of segment 40 being regulated to produce the required extent of motion for loaves of varying size. The tooth 45 is thus advanced under the second pawl 47 (Fig. 2) which engages the tooth and drives the ratchet and conveyor at a slower speed while the loaf is being advanced through the slicer unit.

The mechanism for actuating pawl 47 will now be described: In the other face of the cam 34 there is provided a cam groove receiving the cam roller 48 of an arm 49 which is integral with the slotted arm 50. A link 51, connected to arm 50 by means of a pin set in a block adjustable in the slot of the arm 50, is pivotally connected to an arm 52 of gear segment 53. By regulating the position of the block in the slot of arm 50 the amplitude of the vibratory motion of segment 53 may be varied to compensate for different sizes of loaves in order to advance the loaves clear of the knives of the slicer. Segment 53 meshes with a sector 54 provided with an arm 55 carrying a stud 56 pivotally supporting the pawl 47. Pawls 44 and 47 are equipped with springs 57, which hold the pawls in engagement with the tooth of the ratchet.

Upon the completion of its forward stroke the pawl 44 is returned to its initial position by means of the mechanism actuated by cam 34. Pawl 47 in driving the ratchet advances the second tooth 45a thereof into position to be engaged and driven by pawl 44 at the end of the forward stroke of the pawl 47, the pawl 47 then retreating and awaiting the arrival of tooth 45.

While propelling the loaves the flights 28 of conveyor 29 are held in an upright position by means of rollers 58 carried by the flights 28 and riding on the top of a cam rail 59 supported on shafts 32 and 33. When the rollers 58 reach the end of rail 59 they follow the track 60 which allows the flights gradually to descend from the loaf, and the loaf is thus halted in the slicer unit 61, awaiting the arrival of the next load, whereby it will be pushed through the slicing unit at a relatively low speed while the pawl 47 is driving the ratchet 46. The loaves on entering the slicer unit pass beneath a top tension guide 62x.

The slicer unit 61 is of the conventional type, and is mounted on tie bars 62 connecting the side frames 11 of the machine. The slicer unit is driven by means of a motor 63 driving a chain 64 running over a sprocket 65 and a sprocket 66 attached to the crank shaft 67 of the slicer. The 60 slicing knives are disposed in slots in the bottom of the chute 10 and supported on knife frames connected to the crank shaft 67. Further description of the mounting of the knife frames and their connections to the crank shaft is deemed unnecessary since the same is conventional.

The loaf after having been sliced enters between side guides 68 which are attached to rods 69 slidably in the lugs 70 of brackets 71 connected by a table, and locked in position by set screws 72 to hold the slices of the loaf together. Upon leaving chute 10 the sliced loaves drop onto the table supported by the brackets 71, the loaves being advanced on the table by a conveyor 73 having pushers 74 which travel through slots

in the table and deliver the loaves to the runway 15 of a wrapping machine. Upon entering the runway 15 the loaves enter between flights 76 of an endless conveyor (not shown) which clamp the loaf by its ends and propel the same to the 5 wrapper applying station of the wrapping machine.

The conveyor 13 is driven from the cam shaft 20 by means of a sprocket 77 driving a chain 78 running over a sprocket 79 mounted on a shaft 10 80 supported in brackets 81 attached to the frames 11. The shaft 80 carries a pair of sprockets 82 driving conveyor chains 73 over idler sprockets 83. On the shaft 80 are pivoted the brackets 71, one of which is equipped with a stud 15 and lock nut 84 engaging in the elongated slot 85 of bracket 81. With this arrangement, the brackets 71 can be raised or lowered to the level of the runway of the wrapping machine and when properly located, locked in position by nut 84. 20 The cam shaft 20 is provided with a sprocket 86 which is driven by means of a chain 87 from the main drive of the wrapping machine.

The adjustment of the block by which link 38 is secured to arm 37 to regulate the amplitude 25 of the loaf forward stroke of the chain flight 28 is important because it permits the slicing of narrow loaves to occupy the same proportion of the machine cycle that the slicing of the wide loaves does. The value of this lies in the fact 30 that most of the production in bakeries is on relatively narrow loaves and it is on these loaves which are commonly sliced while soft and hot, that a slow advance resulting in the highest quality of slicing is desired. Therefore it is important that the maximum part of the machine 35 cycle available for slicing be utilized in slicing the narrow loaves, just as it is in slicing the broad loaves and for this purpose in the present device, the adjustment referred to is employed. 40 This result is obtained by increasing the loaf advancing movement per unit of time for broad loaves such as the so called jumbo or double loaves and by decreasing the loaf advancing movement per unit of time through the slicer for 45 narrow loaves. Thus the present machine slices narrow loaves with maximum efficiency and yet can be conveniently adjusted to handle wide loaves, eliminating the necessity of a second machine for this purpose.

What is claimed is:

1. In a bread slicer, the combination with a chute adapted to receive a single file of loaves of bread, of a slicer unit, and cam-actuated means for separating loaves from said file and advancing them to said slicer unit at a relatively high speed and advancing them through the slicer unit at a relatively low speed, the bottom of said chute being provided with longitudinal slots, and said means including conveyor chains 60 provided with flights arranged to travel through said slots, driven and idler sprockets over which said chains are trained, escapement means adapted to arrest the leading loaf in said file and then release the same to permit it to slide down 65 said chute into the path of said flights, and mechanism for driving said driven sprockets at a relatively high speed and then at a relatively low speed.

2. In a bread slicer, the combination with a 70 chute adapted to receive a single file of loaves of bread, of a slicer unit, and means for separating loaves from said file and advancing them to said slicer unit at a relatively high speed and advancing them through the slicer unit at a rela- 75

tively low speed, the bottom of said chute being provided with longitudinal slots, and said means including conveyor chains provided with flights arranged to travel through said slots, driven and 5 idler sprockets over which said chains are trained, escapement means adapted to arrest the leading loaf in said file and then release the same to permit it to slide down said chute into the path of said flights, mechanism for driving 10 said driven sprockets at a relatively high speed and then at a relatively low speed, and adjusting means for varying the amplitude of the high speed and low speed motions of said driven sprockets in order to bring loaves of different 15 sizes into engagement with the slicer unit at high speed and advance them clear of the slicer unit at low speed.

3. The combination with a chute adapted to receive a single file of loaves of bread, of cam- 20 actuated means for separating loaves from said file and advancing them at a relatively high speed and then at a relatively low speed, the bottom of said chute being provided with longitudinal slots, and said means including conveyor chains 25 provided with flights arranged to travel through said slots, driven and idler sprockets over which said chains are trained, escapement means adapted to arrest the leading loaf in said file and then release the same to permit it to slide 30 down said chute into the path of said flights, and mechanism for driving said driven sprockets at a relatively high speed and then at a relatively low speed.

4. The combination with a chute adapted to receive a single file of loaves of bread, of means 35 for separating loaves from said file and advancing them at a relatively high speed and then at a relatively low speed, the bottom of said chute being provided with longitudinal slots, and said 40 means including conveyor chains provided with flights arranged to travel through said slots, driven and idler sprockets over which said chains are trained, escapement means adapted to arrest the leading loaf in said file and then release 45 the same to permit it to slide down said chute into the path of said flights, mechanism for driving said driven sprockets at a relatively high speed and then at a relatively low speed, and adjusting means for varying the amplitude of the high 50 speed and low speed motions of the driven sprockets.

5. The combination with a slicer unit, of means for advancing loaves to said slicer unit at a relatively high speed and advancing them 55 through the slicer unit at a relatively low speed, said means including conveyor chains provided with flights adapted to push the loaves, driven and idler sprockets over which said chains are trained, mechanism for driving the driven 60 sprockets at a relatively high speed and then at a relatively low speed, and adjusting means for varying the amplitude of the high speed and low speed motions of the driven sprockets in order to bring loaves of different sizes into engagement 65 with the slicer unit at high speed and advance them clear of the slicer unit at low speed.

6. Cam-actuated means for advancing loaves at a relatively high speed and then at a relatively low speed, comprising conveyor chains 70 provided with flights adapted to push the loaves, driven and idler sprockets over which said chains are trained, and mechanism for driving the driven sprockets at a constant relatively high speed and then at a constant relatively low 75 speed.

7. Means for advancing loaves at a relatively high speed and then at a relatively low speed, comprising conveyor chains provided with flights adapted to push the loaves, driven and idler sprockets over which said chains are trained, and 5 mechanism for driving the driven sprockets at a relatively high speed and then at a relatively low speed, said mechanism including a shaft to which said driven sprockets are fast, a ratchet fast to said shaft, arms loosely mounted on said 10 shaft, spring-pawls mounted on said arms to engage the teeth of said ratchet, and means for vibrating said arms to cause said pawls successively to engage the teeth of said ratchet and drive said shaft at alternately different speeds. 15

8. Means for advancing loaves at a relatively high speed and then at a relatively low speed, comprising conveyor chains provided with flights adapted to push the loaves, driven and idler sprockets over which said chains are trained, and 20 mechanism for driving the driven sprockets at a relatively high speed and then at a relatively low speed, said mechanism including a shaft to which said driven sprockets are fast, a ratchet fast to said shaft, arms loosely mounted on said 25 shaft, spring-pawls mounted on said arms to engage the teeth of said ratchet, means for vibrating said arms to cause said pawls successively to engage the teeth of said ratchet and drive said shaft at alternately different speeds, and adjusting means for varying the amplitude of the 30 vibratory motion of said arms.

9. The combination with a shaft, of a ratchet fast on said shaft, a pair of arms loose on said 35 shaft, spring-pawls mounted on said arms to engage the teeth of said ratchet, and means for vibrating said arms to cause said pawls successively to engage the teeth of said ratchet and drive said shaft at alternately different speeds.

10. The combination with a shaft, of a ratchet 40 fast on said shaft, a pair of arms loose on said shaft, spring-pawls mounted on said arms to engage the teeth of said ratchet, means for vibrating said arms to cause said pawls successively to engage the teeth of said ratchet and drive said 45 shaft at alternately different speeds, and adjusting means for varying the amplitude of the vibratory motion of said arms.

11. The combination with a slicer unit having a plurality of spaced knives, of a stationary platform adjacent the knives, mechanism for feeding loaves in spaced relation along a runway and depositing a loaf in front of and adjacent said knives on said platform, said mechanism including a loaf forwarding member, means for moving said member at a relatively high speed toward said knives for a distance approximately equal to the spaces between said loaves to advance a succeeding loaf into abutting relation with a loaf in front of said knives, and means 50 synchronized and interrelated and interconnected with said mechanism and said first mentioned means for then moving said member at a relatively low speed toward said knives for a distance approximately equal to the width of a loaf 55 to cause one abutting loaf to push the other through said knives.

12. The combination with a slicing unit having a plurality of spaced knives, of mechanism for feeding loaves in spaced relation along a 70 runway and depositing a loaf in front of and adjacent said knives, said mechanism including a loaf forwarding member, means for moving said member at a relatively high speed toward said knives for a distance approximately 75

equal to the space between said loaves to advance a succeeding loaf into abutting relation with said first mentioned loaf, means for moving said member at a relatively low speed toward said knives for a distance approximately equal to the width of a loaf to cause one abutting loaf to push the other through said knives, and mechanism for adjusting said means to vary the amount of rapid and slow movement to be imparted to said feeding mechanism in accordance with the width of the loaves to be sliced.

13. In a slicing machine, a slicer unit having a plurality of spaced knives, mechanism for advancing a series of loaves along a runway to said knives, comprising a conveyor having spaced loaf forwarding flights, driving connections for imparting a relatively high speed to the flights during a part of each cycle of the machine for feeding loaves in front of and adjacent said knives, and for moving said flights at a relatively low speed for the remainder of the cycle to advance said loaves through said knives, and means for adjusting said connections for varying the distance traveled by said flights at said high and low speed in accordance with the width of the loaves of the series to be sliced.

14. In a bread slicing machine, the combination with a slicer, and means to receive and to feed towards said slicer a row of loaves in constantly upright, contacting, side by side relation, of mechanism for positively pushing through said slicer in a continuous series a plurality of loaves from said row in side by side contacting relation, means to advance each completely sliced loaf from said slicer, said first-named feeding means operating to advance each loaf intermittently from said row for recurrently replenishing the quantum of loaves being so pushed in said series through said slicer, and means for controlling the movement of said pushing mechanism so constructed and arranged that the time interval during which the loaf is being sliced remains substantially constant regardless of the width of loaves pushed through said slicer.

15. The combination with a slicing unit having a plurality of spaced knives, of mechanism for feeding a row of loaves along a runway and for separating the loaves seriatim from said row and depositing each loaf so separated in front of and adjacent to said knives, said mechanism including, a loaf forwarding member, means for moving said member to advance each succeeding separated loaf against each immediately preceding separated loaf to push the latter through said knives, and devices for adjusting said means to vary the amount of movement to be imparted to

said feeding mechanism in accordance with the width of the loaves to be sliced.

16. The combination with a slicer, of a delivery conveyor adjacent the delivery end of said slicer provided with flights spaced to receive the sliced loaves therebetween, and mechanism for periodically pushing successive loaves through said slicer whereby each loaf will be pushed through said slicer and sliced, said mechanism being adjustable to vary the extent the loaves are moved in each cycle, and including means to drive said pushers at different speeds, increasing with the width of the loaves, whereby the period required for slicing each loaf occupies a constant interval of time irrespective of the width of the loaves, and means for synchronizing the movement of said pushers with that of said delivery conveyor to deliver the sliced loaves in the proper relation to said flights.

17. The combination with a slicer, of mechanism for periodically pushing successive loaves through said slicer whereby each loaf will be sliced, said mechanism being adjustable to vary the extent the loaves are advanced in each cycle, and including means to drive said pushers at different speeds, corresponding to the various widths of the loaves, whereby the period required for slicing one loaf occupies a constant interval of time.

18. In a bread slicing machine, the combination with a slicer; means to receive and to feed towards said slicer, a row of loaves in constantly upright, contacting, side by side relation; mechanism for pushing positively through said slicer, in continuous series at all times, a plurality of loaves from said row in contacting, upright, side by side relation; means to advance from said slicer each completely sliced loaf; said first-named feeding means operating to advance intermittently from said row each leading loaf thereof, thereby replenishing recurrently the quantum of loaves being so pushed in continuous series through said slicer, said means for advancing each completely sliced loaf including, a delivery conveyor provided with spaced flights adapted to receive sliced loaves sidewise therebetween from said slicer and transport them sidewise to a wrapping machine, said mechanism for intermittently advancing upright loaves sidewise through said slicer acting to deliver them sidewise between the flights of said conveyor, and means for driving said delivery conveyor in co-ordinated relation with said intermittent feed of the pushers.

ROBERT J. BEUTEL. 55
